UNITED STATES PATENT OFFICE.

HENRY E. RAINAUD, OF MERIDEN, CONNECTICUT, ASSIGNOR TO THE H. E. RAINAUD COMPANY, OF MERIDEN, CONNECTICUT, A CORPORATION OF CONNECTICUT.

DESIGN FOR A SHADE FOR LIGHTING FIXTURE.

Application filed August 15, 1921. Serial No. 492,516. Term of patent 7 years.

To all whom it may concern:

Be it known that I, HENRY E. RAINAUD, a citizen of the United States, residing at Meriden, in the county of New Haven and State of Connecticut, have invented a new, original, and ornamental Design for a Shade for Lighting Fixture, of which the following is a specification, reference being had to the accompanying drawing, forming part thereof.

Fig. 1 is a side elevation of a shade for lighting fixture, showing my new design.

Fig. 2 is a top view of the same, only a part of the ornamentation being shown, it being apparent that the remainder is a repetition of the same.

I claim:

The ornamental design for a shade for lighting fixture, as shown.

HENRY E. RAINAUD.
